[57] CLAIM

The ornamental design for a combined scraper and cover, as shown and described.

DESCRIPTION

FIG. 1 is a perspective view of a combined scraper and cover showing my new design;

FIG. 2 is a reduced top plan view thereof;

FIG. 3 is a side elevational view thereof, the opposite side being a mirror image;

FIG. 4 is a rear elevational view thereof;

FIG. 5 is a front elevational view thereof; and

FIG. 6 is a bottom plan view thereof.
